James M. Conner by Almon, from his

UNITED STATES PATENT OFFICE.

JAMES M. CONNER, OF NEW YORK, N. Y.

DESIGN FOR A FONT OF PRINTING-TYPE.

SPECIFICATION forming part of Design No. 13,830, dated April 3, 1883.

Application filed November 22, 1882. Term of patent 14 years.

To all whom it may concern:

Be it known that I, JAMES M. CONNER, of the city, county, and State of New York, have invented and produced a new and original Design for a Font of Printing-Type, of which the following is a specification.

The nature of my design is clearly shown in the accompanying typographic impression, to which reference is made; and it consists of a light-face inclined letter ornamented by a light curved line curving to the left and extending below the line. In many of the letters these ornamental curved lines—as in the B, C, G, P, R, and S—extend from the upper right-hand portion of the letters; in others—as in the

A, E, F, H, I, J, K, L, M, N, O, Q, U, and W—from about the center of the letter, and in the T, V, X, Y, Z, and symbol & from the base of the letter downward.

The character of the design is preserved in the numerals and lower-case, *sc* that the ornamental curved line is omitted.

Having now described my invention, I claim as new—

The design for a font of printing-type, as shown and described.

JAMES M. CONNER.

In presence of—

WILLIAM V. H. HICKS,
A. SIDNEY DOANE.
